(57) **CLAIM**

The ornamental design for an optical automatic level, as shown and described.

DESCRIPTION

FIG. 1 is a perspective view of an optical automatic level showing our new design;

FIG. 2 is a right side elevational view thereof;

FIG. 3 is a top plan view thereof;

FIG. 4 is a left side elevational view thereof;

FIG. 5 is a rear elevational view thereof; and,

FIG. 6 is a front elevational view thereof.

The bottom surfaces of the optical automatic levels are not part of the design sought to be patented and are therefore not shown. The portions of the optical automatic levels shown in broken lines are not part of the design sought to be patented.
